UNITED STATES PATENT OFFICE.

BERTRON K. BOYD, OF OWOSSO, MICHIGAN.

FLY-TRAP.

1,096,889.

Specification of Letters Patent.

Patented May 19, 1914.

Application filed August 27, 1913. Serial No. 786,823.

To all whom it may concern:

Be it known that I, BERTRON K. BOYD, a citizen of the United States of America, residing at Owosso, in the county of Shiawassee and State of Michigan, have invented certain new and useful Improvements in Fly-Traps, of which the following is a specification, reference being had therein to the accompanying drawings.

10 This invention relates to a fly trap and more particularly to a collapsible or folding fly trap and its object is to provide a very simple and cheap construction which may be quickly and easily folded into a small 15 flat bundle for the purpose of shipping and without the necessity for disconnection or removal of any of the parts.

15 A further object of the invention is to provide a construction in which provision is made for catching dead flies and in which the construction is such that the parts for holding the dead flies may be quickly and easily detached and removed for cleaning the trap.

20 It is also an object of the invention to provide certain other new and useful features in the construction and arrangement of parts all as hereinafter more fully described.

25 To these ends the invention consists in the matters hereinafter set forth and more particularly pointed out in this specification reference being made to the accompanying drawing in which—

30 Figure 1 is a view in side elevation of a device embodying the invention with a portion broken away to show the interior construction; Fig. 2 is a transverse vertical section through the same; and Fig. 3 is a like section showing the trap in folded position.

35 Two rectangular frames 1 are pivotally connected at their upper ends by means of hinges 2 and are arranged to fold toward each other with their adjacent sides in contact or to be spread apart at their lower ends and held in extended position by means of brace bars 3 and 4 arranged in pairs. These bars are pivotally connected at one end and at their outer ends are pivotally attached to the lower ends of the side members of the two frames. The bar 4 of each 40 pair is formed with a lug 5 at one end to engage the upper edge of the bar 3 when the brace is extended and hold the two bars in alinement.

45 Each rectangular frame 1 is covered with

a wire netting 6 and the space between the ends of the two frames when the same are extended, is closed by means of a flexible netting or fabric 7 which is tacked or otherwise secured to the end members of the two frames. A structure which is of conical shape in cross section is thus formed, the sides being closed by the wire screen sides and fabric ends 7.

50 A suitable bottom for the structure is formed by two pivotally connected bottom members each comprising a strip of sheet metal secured at its ends to end strips 8 and turned at right angles along one edge to form a bottom edge flange 9, the pan 10 thus formed being pivotally attached to and supported by the bottom strip 11 of each side frame 1, by means of suitable hooks 12 secured to the inner sides of said strips and adapted to engage openings 13 in the edge flange 9 of the pan. When these bottom members are in position for use they extend upwardly within the structure at an inclination with the upper ends of the two end bars of each member adjacent to each other and these bars of the two members are connected by means of a strip of wire netting or other suitable material 14 secured to the lower edges of the bars and along the upper edges of the pan 10. These bottom members thus together form a bottom closure for the receptacle which is of inverted V-shape in cross section and extends from one end wall to the other of the structure, the lower side portions of the bottom being formed by the two pans 10 and the middle portion by the screen which serves to connect the two parts of the bottom and which screen is formed with a series of openings 15 along its bending line or at the apex of the bottom. It is obvious that the two members forming the bottom may be hinge connected by other means than the wire fabric 14 and that instead of the openings 15 being provided therein for the entrance of the flies into the trap, two separate strips of fabric may be secured to the members with a space between their adjacent edges forming a longitudinal slot for the entrance of the insects.

55 As the flies die in the trap they drop upon the conical bottom and lodge in the pans. The trap may be quickly and easily cleaned by simply lifting these pans out of engagement with the hooks 12, and for conven-

105

110

ience in handling and shipping, the whole structure may be quickly folded into a flat package by breaking the braces upwardly and swinging the side frames toward each other with their adjacent sides in contact. When the frames are so folded, the bottom members will turn upon the hooks which support them and will lie within the planes of the side members of the two rectangular frames of the structure. It is therefore unnecessary to remove any of the parts when the device is folded and when the structure is extended for use, the parts are all in place.

Obviously, other changes may be made in the construction and arrangement of parts without departing from the spirit of my invention and I do not therefore limit myself to the particular form or arrangement shown.

Having thus fully described my invention what I claim is:—

1. In a fly trap, the combination of a pair of side members pivotally connected at their upper ends, a bottom pivotally connected at its outer sides to the side members to fold upwardly between said members when the same are turned toward each other upon their pivotal connection and having an inverted V-shape in cross section when the frames are spread apart at their lower ends and an entrance opening at the apex of said bottom, and means for closing the ends of the space between said side members.

2. In a fly trap, the combination of a pair of rectangular frames pivotally connected at their upper ends, walls of flexible material extending across between the ends of the frames and secured thereto, bottom members pivotally and detachably connected adjacent to their outer edges to said frames near the lower ends thereof and extending upward between the frames with their upper edges adjacent to each other and connected to permit said members to be folded toward each other when the said frames are turned upon their pivotal connection, the bottom formed by said members being provided with an entrance opening.

3. In a fly trap, the combination of a pair of rectangular frames pivotally connected at their upper ends and adapted to swing toward and from each other at their lower ends, a screen closing each frame and forming the side walls of the trap, end walls of flexible material secured to the ends of said frames, brace bars extending between and pivotally connected to the frames, a bottom having an inverted V-shape in cross section with the apex extending upwardly between the frames and formed with an entrance opening at said apex, and means for detach-

ably and pivotally connecting said bottom at its outer edges to said frames.

4. In a fly trap, the combination of a pair of rectangular open frames pivotally connected at their upper ends, a bottom comprising a pair of members connected at their upper edges to turn toward and from each other and pivotally connected at their lower edges to said frames, said members each formed with a lower imperforate portion forming a pan and an upper screen portion, an inlet opening being provided in said bottom at the upper adjacent edges of the members, and means extending between the frames to hold said frames turned upon their pivotal connection and spaced apart.

5. In a fly trap, the combination of a frame having walls formed of wire screen, a bottom comprising a pair of members connected at their adjacent upper edges and extending upwardly within the frame at an inclination to each other, each member comprising an imperforate lower portion forming a pan and a perforate upper portion, said bottom being provided with an entrance opening between the connected upper edges of said members, and hooks on the frame to engage the lower edges of the members of the bottom and detachably support the same.

6. In a fly trap, the combination of a pair of rectangular frames pivotally connected at their upper ends, a panel of wire screen in each frame forming a side wall of the fly trap, end walls formed of flexible material secured to said frames and extending across between the same when said frames are turned upon their pivotal connection to space their lower ends apart, brace members pivotally attached to the frames near their lower ends and jointedly connected together, a bottom comprising a pair of members connected at their upper edges to turn toward and from each other at their lower edges and each comprising an imperforate lower edge portion forming a pan, and an upper screen portion, said members being arranged to extend upwardly at an inclination to each other between said frames and form a bottom having an inverted V-shape form in cross section with an entrance opening at the apex thereof, and hooks on the frames near their lower ends to engage the lower edges of the members of the bottom and pivotally and detachably support the bottom.

In testimony whereof I affix my signature in presence of two witnesses.

BERTRON K. BOYD.
